L. E. FRENCH.
PRIMING DEVICE ATTACHMENT,
APPLICATION FILED OCT. 12, 1917.

Patented Apr. 15, 1919.

Attorney

UNITED STATES PATENT OFFICE.

LAURENCE E. FRENCH, OF SEBASTOPOL, CALIFORNIA.

PRIMING-DEVICE ATTACHMENT.

1,300,597.

Specification of Letters Patent. Patented Apr. 15, 1919.

Application filed October 12, 1917. Serial No. 196,141.

To all whom it may concern:

Be it known that I, LAURENCE E. FRENCH, a citizen of the United States, residing at Sebastopol, in the county of Sonoma and 5 State of California, have invented certain new and useful Improvements in Priming-Device Attachments, of which the following is a specification.

This invention relates to priming devices 10 for internal combustion engines and it is the dominant object of the invention to provide a priming device having novel operating means whereby the cut-off means therefor can be actuated by foot or by hand for 15 admitting the passage of a priming fluid to the engine cylinders.

Another and equally important object of the invention is to provide means for allowing the cut-off means to be maintained in 20 open position subsequent to the starting of the engine, thereby permitting the cylinders of the same to be brought to proper working temperatures.

Other independent objects are to provide 25 features of construction of portions of the attachment which tend toward the attainment of the above aims irrespective of the relation in which they are used.

Other objects will be in part obvious and 30 in part pointed out hereinafter.

The invention accordingly consists in the features of construction, combination of elements and arrangement of parts which will be exemplified in the construction herein- 35 after set forth, and the scope of the application of which will be indicated in the following claim.

In the accompanying drawing, wherein is 40 shown one of various possible embodiments of my invention I have illustrated a vertical section through a motor driven vehicle dashboard showing the improved priming device attachment applied thereto and having parts of the same in section.

45 Similar characters of reference refer to similar parts throughout the several views of the drawings.

Having more particular reference to the drawings, D represents the dashboard of a 50 motor driven vehicle and F the footboard of the same.

Passing through a portion of the dashboard D and secured to the same through the medium of locking nuts is a supporting 55 bar 1, to which metal straps 2 having their free ends connected by bolts 3 are secured;

the said straps carrying a fuel tank 4 therein. Connected to the fluid outlet port of the fuel tank 2 is a conduit 5, the free end of which extends to a point in proximity of the dash- 60 board D.

Secured to the rear side of the dashboard D by means of bolts 6 is a bracket 7 having a screw threaded opening formed therein for receiving a complementally screw threaded 65 portion of a rotary valve casing 8. Rotatably mounted in the casing 8 is a valve 9 having a lever 10 fixedly mounted on one extremity thereof and provided with a plurality of openings, the purpose of which will be subsequently apparent. A second conduit 11 extends from the valve casing 8 into engagement with the cylinders of the internal combustion engine E. 70

Passing through a suitable slot or way 75 formed in the lower portion of the dashboard D is a tubular casing member 12, this casing member being supported upon a plate 13 arranged over the said slot and secured to the dashboard by means of screws 80 14 or other suitable fastening devices. A plunger rod 15 is slidably arranged in the tubular body 12 and has the inner end of the same pivotally connected to the lever 10 by means of a suitable connection passing 85 through one of the openings formed therein, while the remaining end of the plunger rod is notched as at 16 and provided with a head 17. Screw threaded guide caps 18 are turned into engagement with comple- 90 mentally threaded portions formed on the tubular body 12 and slidably receive the plunger rod 15 therethrough. As will be noted, the plunger rod 15 when moved in- 95 wardly to its full extent will have the notch 16 formed therein engaged with the adja- cent portion of the outer cap 18, thus, serv- ing as means for maintaining the plunger rod in its innermost position against the ten- 100 sion of an expansible coil spring 19 arranged about a portion of the same within the tubu- lar body 12.

To permit operation of the cut-off means or valve from the front of the machine when cranking the same manually, a wire 20 or 105 suitable connection is passed through the remaining opening formed in the lever 10 and extends through the mesh of the radi- 110 ator construction of the vehicle to a point slightly beyond the same, whereupon it is looped to facilitate engagement therewith.

It is to be noted, that the fuel tank 4 is

mounted above the level of the valve and as a consequence, the flow of combustible fuel therefrom into the various cylinders of the engine E is permitted.

5 When operating the priming device from the operator's seat of the vehicle by foot, the head 17 of the plunger rod 16 is engaged by the foot of user and moves inwardly against the tension of the spring until the 10 notched portion 16 engages over the adjacent portion of the guide cap 18. When in this position, the lever 10 will have been moved to full open position thereby admitting the passage of fuel from the tank 4 to the cylinders of the engine E and effectively 15 priming the same to facilitate starting thereof. When the engine has run for the desired period and the cylinders have been brought to proper working temperatures, 20 the head 17 may be moved slightly upwardly by the toe of the foot of the operator, thus disengaging the notched portion 16 from the guide cap 18 and permitting the 25 expansible spring 19 to return the plunger rod to its normal or closed position, thus discontinuing the passage of fuel from the fuel tank to the engine cylinders. When the car is cranked from the front thereof, the 30 valve may be operated by the wire 20. By pulling the wire forwardly the lever 10 will be rocked in a direction to open the valve and also will move the plunger rod 15 in-

wardly whereupon the notched portion 16 will engage with the adjacent portion of the guide cap 18, thus maintaining the valve in its open position until the engine has run for a sufficient time in order that the cylinders of the same may be brought to the proper temperatures. At this time, the plunger rod 15 may be disengaged by moving the head 17 slightly upwardly to disengage the notched portion 16 from the guide cap 18.

Manifestly, the construction shown is capable of considerable modification and such modification as is within the scope of my claim, I consider within the spirit of my invention.

I claim:—

A priming device attachment, including, 50 in combination with a vehicle dashboard, a fuel tank, a rotary valve arranged below and having connection with said fuel tank, a lever secured to the rotary valve, a spring pressed plunger rod pivotally connected to 55 the lever and extending through the dashboard, said rod being provided with means for maintaining the same in depressed position at times, and hand operated means pivotally engaged with said lever.

In testimony whereof, I affix my signature hereto.

LAURENCE E. FRENCH.
